UNITED STATES PATENT OFFICE.

JOHN J. KEENAN, OF NEW YORK, N. Y.

EMERGENCY TRAFFIC BARRIER.

Application filed January 19, 1924. Serial No. 387,400.

To all whom it may concern:

Be it known that I, JOHN J. KEENAN, a citizen of the United States, and a resident of New York, in the county of New York and State of New York, have invented certain new and useful Improvements in an Emergency Traffic Barrier, of which the following is a full, clear, and exact specification.

10 This invention relates more particularly to a class of safety apparatus. My invention has for its object primarily to provide a barrier designed to be employed on highways, such as on the streets of cities, 15 at railway crossings and elsewhere, for preventing the occurrence of accidents to persons and travelling vehicles by causing their movements to be timely obstructed from moving across the highway, and which is 20 also of a form whereby travelling vehicles in particular on arriving at a dangerous locality after the barrier has been positioned for protective purposes may in emergency be enabled to pass by forcing the barrier 25 upon the highway to allow the vehicle to travel thereover for being freed of the impending danger. The invention resides mainly in the provision of two supports adapted to be fixed in spaced relation above 30 a trough provided across a highway, and on the supports is movably carried a flexible guard line for being raised above and lowered to the highway across the space between the supports. On the central portion of the 35 guard line between the supports is provided means automatically operative to lower and yieldingly hold the guard line normally at the entrance of the trough, and spaced posts are provided for being pivotally mounted 40 between the supports so as to be swung inwardly and outwardly of the trough to and from vertical positions for elevating the portion of the guard line between the supports 45 yieldingly above the surface of the highway for serving to obstruct the passage of persons and vehicular traffic at the locality.

Other objects of the invention are to construct each post with hingedly connected lower and upper parts whereby the upper 50 parts when in vertical positions above the highway may be swung transversely of the trough to the highway by the guard line being likewise forced to the highway, in order to permit especially travelling vehicles when 55 in immediate danger following the elevation of the guard line to swing the guard line and

move thereover to safety; and to provide an emergency traffic barrier of a simple, efficient and durable construction which may be made of appropriate material in any suitable size.

With these and other objects in view, the invention will be hereinafter more fully described with reference to the accompanying drawing forming a part of this specification in which similar characters of reference indicate corresponding parts in all the views, and will then be pointed out in the claims at the end of the description.

In the drawing, Figure 1 is a fragmentary view, partly in section, taken through a trough or excavation provided across a highway, showing one form of my improved emergency traffic barrier applied thereto.

Fig. 2 is a fragmentary view showing a plan taken on the line 2—2 of Fig. 1, and

Fig. 3 is an enlarged fragmentary detail sectional view taken on the line 3—3 of Fig. 1.

The apparatus or barrier has two supports or uprights or posts 10 and 11 which in practice are adapted to be suitably mounted in fixed vertical positions in proximity to the ends of a trough or excavation, as 12, when provided across a highway, as 13, such as a railway crossing or street crossing of a city or elsewhere for travel of pedestrians and vehicles, and the trough may be of a length so that it extends across the sidewalks or pathways, as 14, 15, for pedestrians when provided along each side of the highway. When the apparatus is employed on a highway having the sidewalks or pathways 14, 15 the supports 10, 11 are mounted in the trough 12 at the outermost sides of the pathways, and the supports are of lengths so that their upper ends terminate at suitable heights above the surface of the highway, while the trough is preferably of greater depth than the lengths of the portions of the supports above the highway.

The supports or uprights 10, 11 are of similar formations, and in the upper end of each support may be a groove or passage 16, and rotatably mounted in the 105 grooves of the supports may be pulleys 17, 18. Bracketed, at 19, to opposite sides of the supports, and under the grooves 16 are revolvable pulleys 20, 21, and carried on the supports is a guard line 22. This guard line 110 may be of any suitable flexible material, such as a cable or chain 22^a which is of a

length so that it is movably carried on the supports over the pulleys 17, 18 and 20, 21 with its central portion spanning the highway 13 and sidewalks 14, 15, and the guard line is of a length to permit of being lowered to the entrance of the trough 12 without the end portions of line separating from the pulleys of the supports.

The cable or chain 22^a is adapted to be normally disposed in the entrance of the trough 12 by means of one or a suitable number of weights, as 23, each of which are suspended from the main cross line 22^a by a flexible line or chain 24. The lines or chains 24 are of lengths so that the weights will automatically move downwardly in the trough sufficient distance to yieldingly hold the cable 22^a at the entrance of the trough, and the lines 24 may also be of lengths so that when the cable 22^a is elevated above the trough to a distance approximately on a similar longitudinal plane to the upper ends of the supports the weights will still remain in the trough. On the ends of the cable 22^a are two weights 25, 26 which are automatically movable upwardly and downwardly in the trough 12, and these weights are adapted to partly counterbalance the weights 23 in order to relieve the strain on the cable 22^a when elevated above the highway.

Serving as means to elevate the guard line 22 above the trough for obstructing travel on the highway in emergency, in the upper parts of the trough 12 adjacent the supports 10, 11 are pivoted, at 27, the lower ends of two posts 28, 29 which are preferably of similar formations as well as being of heights similar to the heights of the supports 10, 11. On the pivoted ends 27 of the posts 28, 29 and extending downwardly in the trough 12 are two segmental worms 30, 31 preferably of the shapes of quadrants, and these worms are of sizes so that one of their angular edges are disposed lengthwise of the trough at its entrance. The segmental worms are also disposed so that their curved toothed edges are in opposed relation as well as being disposed toward the center of the trough for causing the posts 28, 29 to be swung upwardly and downwardly to and from the entrance of the trough to vertical positions above the highway. In the upper end of each of the posts 28, 29 may be a groove or passage 32, and in these grooves may be pairs of spaced pulleys 33, 33^a and 34, 34^a, respectively, between which the cable or chain 22^a of the guard line 22 is movable when the posts are in vertical positions above the highway.

Leading from a suitable part of the trough 12 may be a pipe 35 for draining the trough of water accumulating therein, and in the trough on its bottom below the worms 30, 31 may be a number of spaced

bearings, as 37. Journalized in these bearings is a shaft 38 of a length so that it extends lengthwise of the trough under the segmental worms as well as extending some distance beyond the segmental worm 30. On the shaft 38 are two spaced worms 39, 40 which are in mesh with the segmental worms 30, 31. The shaft 38 may be driven by any suitable power generating means, though I prefer to employ in the trough at the extending end of the shaft an electric motor, as 41, of an appropriate reversible type. On the drive shaft of the motor may be a pinion 42 which is in mesh with a gear 43 held on the shaft 38. When the motor is driven accordingly the pinion 42 and gear 43 will be rotated for driving the shaft 38 and worms 39, 40. The segmental worms 30, 31 will then be partly rotated for causing the posts 28, 29 to be simultaneously swung to lowered positions toward each other in the entrance of the trough. The weights 23 of the guard line will then automatically move downwardly in the trough for causing the chain 22^a to be lowered to the entrance of the trough on the posts so that traffic on the highway may travel over the barrier. With the reverse operation of the motor 41 the pinion 42, gear 43 and shaft 38 will be reversely driven for moving the segmental worms upwardly in the trough, and in turn the posts 28, 29 will be swung upwardly to vertical positions above the trough. With the upward movement of the posts the chain 22^a will be engaged by the pulleys 33, 34 of the posts for being elevated across the highway between the supports 10, 11 to obstruct the travel of traffic in emergency. The weights 25, 26 of the guard line then serve by their automatic downward movement in the trough to ease the strain of the weights 23 on the chain 22^a to permit the chain 22^a to be relatively readily elevated.

In order to prevent persons from attempting to move under the chain 22^a on the pedestrian pathways when the guard line is elevated, I may provide two corresponding gates, as 44, 45. The gates may be of any suitable construction, though each gate illustrated has a fixed bar or post 46 extending upwardly above the highway from the straight angular edge of each of the segmental worms 30, 31 which is adapted to be positioned at the entrance of the trough when the guard line is elevated, and extending from the post 46 of each of the gates to the segmental worm of the gate are a number of curved rods or bars 47. The posts 46 of the gates are in spaced proximity to the posts 28, 29, and the rods 47 are relatively spaced apart at distances so that the gates when elevated above the trough will extend across the pathway 14, 15 of the highway to prevent pedestrians

from crossing under the chain 22^a of the guard line. The gates 44, 45 are fixed to the segmental worms 30, 31 to permit the gates to be swung into the trough when the segmental worms are operated, as above explained, for allowing the guard line 22 to lower to the trough.

For the purpose of permitting the chain 22^a and the chains 24 to be swung to the 10 face of the highway when the guard line is elevated so that a travelling vehicle when in danger by failure to move beyond the barrier before being raised may pass to safety, each of the posts 28, 29 are preferably formed 15 of a lower portion 48 and an upper portion 49. The lower portion 48 of each of the posts 28, 29 includes the pivoted part 27, while the upper portion of each post embraces practically the whole of the portion 20 adapted to extend above the trough when the posts are swung to vertical positions. The lower end part of one face of the upper portion of each of the posts may be cut-out, as at 50, and the ends of the lower and upper 25 portion of each post are pivoted together, at 51, to allow the upper portions of both posts to be swung in one direction upon the highway. In the cut-outs 50 of the posts may be provided cushions or springs 52, 53 which 30 are tensioned for serving to yieldingly force the upper portions of the posts when swung upon the highway to their vertical positions above the trough. Thus when a travelling vehicle on approaching the guard line after 35 its elevation from a direction toward the faces of the posts opposite to the springs 52, 53, and in emergency the vehicle may be caused to contact with the chain 22^a. The chain and the upper parts of the posts will 40 then be swung on their pivots against the tension of the springs 52, 53 to the surface of the highway for allowing the vehicle to pass over the chain to safety. After the vehicle has passed entirely over the chain the 45 tension of the springs will cause the posts to swing upward to their normal positions and the posts will likewise carry the chain upwardly across the highway and sidewalk.

In the foregoing description, I have embodied the preferred form of my invention, but I do not wish to be understood as limiting myself thereto, as I am aware that modifications may be made therein without departing from the principle or sacrificing any 55 of the advantages of this invention, therefore, I reserve to myself the right to make such changes as fairly fall within the scope thereof.

Having thus described my invention, I 60 claim as new and desire to secure by Letters Patent:—

1. An emergency traffic barrier, comprising two supports for being fixed in spaced relation above a trough provided across a 65 highway, a flexible guard line movably car-

ried on the supports for being raised above and lowered to the highway across the space between the supports, means on the central portion of the guard line between the supports, automatically operative to lower and 70 yieldingly hold the guard line normally at the entrance of the trough, and means operative for elevating the portion of the guard line between the supports yieldingly above the surface of the highway. 75

2. An emergency traffic barrier, comprising two supports for being fixed in spaced relation above a trough provided across a highway, a flexible guard line movably carried on the supports for being raised above 80 and lowered to the highway across the space between the supports, means on the central portion of the guard line between the supports, automatically operative to lower and yieldingly hold the guard line normally at 85 the entrance of the trough, means at the ends of the guard line, automatically operative to partly counterbalance the force of the pull of the automatic lowering means imposed on the central portion of the guard line, and 90 means operative for elevating the portion of the guard line between the supports yieldingly above the surface of the highway.

3. An emergency traffic barrier, comprising two supports for being fixed in spaced 95 relation above a trough provided across a highway, a flexible guard line movably carried on the supports for being raised above and lowered to the highway across the space between the supports, means on the central portion of the guard line between the supports, automatically operative to lower and yieldingly hold the guard line normally at the entrance of the trough, means operative 100 for elevating the portion of the guard line between the supports yieldingly above the surface of the highway and power driving means operative for operating said elevating means. 105

4. An emergency traffic barrier, comprising two supports for being fixed in spaced relation above a trough provided across a highway, a flexible guard line movably carried on the supports for being raised above 110 and lowered to the highway across the space between the supports, means on the central portion of the guard line between the supports, automatically operative to lower and yieldingly hold the guard line normally at the entrance of the trough, means at the ends 115 of the guard line, automatically operative to partly counterbalance the force of the pull of the automatic lowering means imposed on the central portion of the guard line, means 120 operative for elevating the portion of the guard line between the supports yieldingly above the surface of the highway, and power driving means operative for operating said elevating means. 125

5. An emergency traffic barrier, comprising 130

ing two supports for being fixed in spaced relation above a trough provided across a highway, a flexible guard line movably carried on the supports for being raised above and lowered to the highway across the space between the supports, means on the central portion of the guard line between the supports automatically operative to lower and yieldingly hold the guard line normally at the entrance of the trough, and spaced posts pivoted between the supports for being swung inwardly and outwardly of the trough to and from vertical positions for elevating the portion of the guard line between the supports yieldingly above the surface of the highway and each post having hingedly connected lower and upper parts whereby the upper parts of all the posts when in vertical positions above the highway may be swung transversely of the trough to the highway by the guard line being likewise forced to the highway.

6. An emergency traffic barrier, comprising two supports for being fixed in spaced relation above a trough provided across a highway, a flexible guard line movably carried on the supports for being raised above and lowered to the highway across the space between the supports, means on the central portion of the guard line between the supports, automatically operative to lower and yieldingly hold the guard line normally at the entrance of the trough, means at the ends of the guard line, automatically operative to partly counterbalance the force of the pull of the automatic lowering means imposed on the central portion of the guard line, and spaced posts pivoted between the supports for being swung inwardly and outwardly of the trough to and from vertical positions for elevating the portion of the guard line between the supports yieldingly above the surface of the highway and each post having hingedly connected lower and upper parts whereby the upper parts of all the posts when in vertical positions above the highway may be swung transversely of the trough to the highway by the guard line being likewise forced to the highway.

50 7. An emergency traffic barrier, comprising two supports for being fixed in spaced relation above a trough provided across a highway, a flexible guard line movably carried on the supports for being raised above and lowered to the highway across the space between the supports, means on the central portion of the guard line between the supports, automatically operative to lower and yieldingly hold the guard line normally at the entrance of the trough, spaced posts pivoted between the supports for being swung inwardly and outwardly of the trough to and from vertical positions for elevating the portion of the guard line between the supports yieldingly above the

surface of the highway and each post having hingedly connected lower and upper parts whereby the upper parts of all the posts when in vertical positions above the highway may be swung transversely of the trough to the highway by the guard line being likewise forced to the highway, and power driven means operative for simultaneously raising and lowering the posts into and out of the trough. 75

8. An emergency traffic barrier, comprising two supports for being fixed in spaced relation above a trough provided across a highway, a flexible guard line movably carried on the supports for being raised above and lowered to the highway across the space between the supports, means on the central portion of the guard line between the supports, automatically operative to lower and yieldingly hold the guard line normally at the entrance of the trough, means at the ends of the guard line, automatically operative to partly counterbalance the force of the pull of the automatic lowering means imposed on the central portion of the guard line, spaced posts pivoted between the supports for being swung inwardly and outwardly of the trough to and from vertical positions for elevating the portion of the guard line between the supports yieldingly above the surface of the highway and each post having hingedly connected lower and upper parts whereby the upper parts of all the posts when in vertical positions above the highway may be swung transversely of the trough to the highway by the guard line being likewise forced to the highway, and power driven means operative for simultaneously raising and lowering the posts into and out of the trough. 90

9. An emergency traffic barrier, comprising two supports for being fixed in spaced relation above a trough provided across a highway, a flexible guard line movably carried on the supports for being raised above and lowered to the highway across the space between the supports, weights on the central portion of the guard line between the supports, automatically movable to lower and yieldingly hold the guard line normally at the entrance of the trough, and spaced posts pivoted between the supports for being swung inwardly and outwardly of the trough to and from vertical positions for elevating the portion of the guard line between the supports yieldingly above the surface of the highway and each post having hingedly connected lower and upper parts whereby the upper parts of all the posts when in vertical positions above the highway may be swung transversely of the trough to the highway by the guard line being likewise forced to the highway. 110

10. An emergency traffic barrier, comprising two supports for being fixed in spaced

relation above a trough provided across a highway, a flexible guard line movably carried on the supports for being raised above and lowered to the highway across the space between the supports, weights on the central portion of the guard line between the supports, automatically movable to lower and yieldingly hold the guard line normally at the entrance of the trough, spaced posts pivoted between the supports for being swung inwardly and outwardly of the trough to and from vertical positions for elevating the portion of the guard line between the supports yieldingly above the surface of the highway and each post having hingedly connected lower and upper parts whereby the upper parts of all the posts when in vertical positions above the highway may be swung transversely of the trough to the highway by the guard line being likewise forced to the highway.

12. An emergency traffic barrier, comprising two supports for being fixed in spaced relation above a trough provided across a highway, a flexible guard line movably carried on the supports for being raised above and lowered to the highway across the space between the supports, weights suspended on the central portion of the guard line between the supports for automatically moving in the trough to lower and yieldingly hold the guard line normally at the entrance of the trough, weights at the ends of the guard line for also automatically moving in the trough to partly counterbalance the force of the pull of the weights imposed on the central portion of the guard line, two spaced posts pivoted between the supports for being swung inwardly and outwardly of the trough to and from vertical positions for elevating the portion of the guard line between the supports yieldingly above the surface of the highway, and each post having hingedly connected lower and upper parts whereby the upper parts of both posts when in vertical positions above the highway may be swung transversely of the trough to the highway by the guard line being likewise forced to the highway, a gate on the upper part of each post, and power driven means operative for simultaneously raising and lowering the posts into and out of the trough.

13. 11. An emergency traffic barrier, comprising two supports for being fixed in spaced relation above a trough provided across a highway, a flexible guard line movably carried on the supports for being raised above and lowered to the highway across the space between the supports, weights suspended on the central portion of the guard line between the supports, automatically movable in the trough to lower and yieldingly hold the guard line normally at the entrance of the trough, weights at the ends of the guard line, for also automatically moving in the trough to partly counterbalance the force of the pull of the weights imposed on the central portion of the guard line, and spaced posts pivoted between the supports for being swung inwardly and outwardly of the trough to and from vertical positions for elevating the portion of the guard line between the supports yieldingly above the surface of the highway and each post having hingedly connected lower and upper parts whereby the upper parts of all the posts when in vertical positions above the highway may be swung transversely of the trough to the highway by the guard line being likewise forced to the highway.
